UNITED STATES PATENT OFFICE.

EDWIN G. PICKERING, OF NEAR DAYTON, OHIO.

IDENTIFYING-CARD.

1,245,615.

Specification of Letters Patent. Patented Nov. 6, 1917.

Application filed July 7, 1917. Serial No. 179,190.

To all whom it may concern:

Be it known that I, EDWIN G. PICKERING, a citizen of the United States, residing near Dayton, in the county of Montgomery and State of Ohio, have invented a new and useful Improvement in Identifying-Cards, of which the following is a specification.

This invention relates to new and useful improvements in identifying cards.

The principal object of my invention is to provide an identifying card which may be readily and firmly attached to the coat of the wearer without the necessity of employing separate fastening means. By providing the cards in tape form, they may be easily scored, printed and cut, provision being made for writing a signature on one side of the card and typewriting it on the other. As the fastening means is integral with the card itself, there is no necessity for employing a pin or other fastening element to attach the identifying part to the coat of the wearer, although such fastening elements may be employed, if desired, without departing from the spirit of the invention.

The preferred form of embodiment of my invention is illustrated in the accompanying drawings, of which Figure 1 is a plan view of a tape or strip of three cards containing the improved identifying parts. Fig. 2 is a plan view of the rear side of one of said cards, whose identifying part is adapted to contain a typewritten signature. Fig. 3 is a plan view of a coat to the lapel of which my identifying card is attached. And Fig. 4 is a vertical section taken through said lapel, showing how the identifying part of the card is supported.

Throughout the specification and drawings, similar reference characters denote corresponding parts.

Referring to the drawings, the numeral 1 designates preferably rectangular cards which are preferably, though not necessarily, made up in the tape or strip form shown in Fig. 1. When made up in such form, they may be readily cut or otherwise severed from each other along the scored lines 2.

Formed as follows in each of the cards 1 is an inverted T-shaped identifying part for attachment to the coat of the wearer. Extending from side to side of the bottom of the card 1 is a preferably rectangular part 3 which forms the cross of the T. From this part 3 there extends to the top of the card the leg 4 of the T, which is much nar-

rower than its cross portion 3 and is marked off on the card 1 by the parallel score lines 5 5.

The lateral edge of the cross part 3 which is nearest the leg portion 4 of the T part of the card, is cut or slit along the lines 6 6, each of said lines extending from one side edge of the card 1 to the leg portion 4, for a purpose to be hereinafter described. 60 The other lateral edge of the cross part 3 of the T portion of the card is the lower end of the latter, a short distance above which there is a horizontal line 7 adapted to receive the written signature of the 70 wearer of the identifying part of said card. (See the lower card 1 in Fig. 1.)

In use, the card 1 may be mailed to an individual by a lodge, class or other organization to which he belongs, as an identifying medium to be worn by him at one of its meetings, entertainments or other functions. The card may also be given to him at the door, whereupon he will write his signature on the line 7, and tear off, along the score 80 lines 5 5, the two sides of the card between the slits 6 6 and the upper end of the card, leaving the T shaped identifying part to be attached to the lapel of his coat in the manner to be hereinafter described. On the 85 other hand, when the individual enters the door of the lodge or other meeting place, it may be arranged for him to pass a person at a typewriter containing a strip of the cards 1 with the reverse sides thereof facing the type. The person at the machine may then typewrite the name as on the card shown in Fig. 2, in which there is no need of guiding line 7, and then tear out and 90 hand to the passing individual the identifying T part bearing the latter's name for attachment to his coat lapel as follows.

Referring to Figs. 3 and 4, the wearer, after the identifying part is withdrawn from the card 1, will thrust the leg portion 4 thereof through the buttonhole 8 of his coat lapel 9 in such a manner that the face of the cross part 3 bearing his name will be exposed to view. The leg portion 4 of the identifying part of the card is thrust through the buttonhole 8 far enough to enable the cross part 3 to assume the position shown in Figs. 3 and 4, or one in which the wearer's name will be prominently displayed. During the time it is worn, the leg portion 4 of the identifying part of the card 105 will act as a flange behind the coat lapel to 110

firmly maintain the cross part 3 in its best displaying position. In a like manner, the displaying part of the card may be secured to the pocket portion 10 of the wearer's coat, 5 if desired.

I do not wish to be limited to the details of construction and arrangement herein shown and described, and any changes or modifications may be made therein within 10 the scope of the subjoined claims.

Having described my invention, I claim:

1. A series of identifying cards detachably connected together in tape form, each card having marked off thereon a T-shaped 15 identifying part, the cross portion of said identifying part adapted to receive a written signature on one side and a typewritten name on the other, and having a leg portion that extends from the top of the card to its 20 cross portion and is adapted to be thrust through a buttonhole of the wearer's coat, for firmly securing thereto the cross portion

of the card in a position to prominently display the wearer's name.

2. A series of identifying cards detachably connected together in tape form, each card having a separable identifying part, 25 said part being of T-shape and having a leg portion scored from the top of the card to a cross portion formed at the bottom thereof, the edge of said cross portion nearest the leg portion, being cut in to the latter from each side of said card, whereby the identifying part may be readily torn from the card so that its leg portion may be thrust through 30 a buttonhole in the wearer's coat to hold the cross portion in a displaying position thereon.

In testimony whereof I have hereunto set my hand this 5th day of July, 1917.

EDWIN G. PICKERING.
